UNITED STATES PATENT OFFICE

ERNST EMANUEL HOLMQVIST, OF STOCKHOLM, SWEDEN, ASSIGNOR TO ELVIRA VICTORIA HOLMQVIST, OF STOCKHOLM, SWEDEN

LIGHTING APPARATUS

Application filed March 28, 1929, Serial No. 350,702, and in Sweden March 30, 1928.

My invention relates to lighting apparatus and more particularly to reflectors in combination with electric lamps. My invention has for its object primarily to provide a reflector construction designed to be employed especially in conjunction with an electrical light source when supported at a height in a room, whereby the rays of light will be radiated in substantially horizontal and downward directions. Another object is to provide that the ceiling of the room will receive no illumination from the lighting apparatus, that the upper part of the side walls of the room will receive direct illumination from the light source, that the floor and the lower part of the walls will receive only diffused light from the reflectors, and that the walls will receive only a minimum of the diffused light. Another object is to provide, that the lighting reflector surfaces, which are visible to an eye of normal position in the room, will be of such a size with regard to the total light emanation and will have such a uniformly distributed light emanation, that the eye will not be unnecessarily dazzled by the lighting from the reflectors.

My invention thus effects that only a minimum of light will be absorbed by the ceiling and the side walls, that pictures etc. on the upper part of the side walls will be well illuminated with the most effective direct light, that objects on the floor will be well illuminated by diffused light, and that the eye in normal position in the room will not be dazzled by lighting surfaces of unnecessarily high intensity; all cooperating to effect a pleasant and high-efficient illumination of the room.

A further object of this invention is to provide the reflectors with adjustable attaching means for varying the relative positions of light source and the reflectors, whereby the lighting apparatus can be adapted for use in rooms of different size.

The reflectors must be plane for distributing the light in desired manner from the greatest height in the room and for giving a pleasant view of the lighting apparatus in daylight and lighting time.

In the accompanying drawings I have illustrated a lighting apparatus constructed and arranged in accordance with my invention, but it will be understood that I contemplate minor changes or alterations, which I consider within the scope of my claims without departing from the spirit of my invention.

In the drawings:—

Fig. 1 is a side view of a lighting apparatus with two reflectors, being attached to the ceiling of a room, part of which is shown in section.

Fig. 2 is a view showing a lighting apparatus with three reflectors.

Fig. 3 is a sectional elevation showing the lighting apparatus except that the right part of the reflectors are broken away.

Fig. 4 is a fragmentary view showing a plan of the lighting apparatus.

Referring to the drawings by numerals, each of which is used to indicate same or similar parts of the different figures:—

The source of light 10 with lamps 17 is secured to the ceiling 11 of a room, of which is shown a side wall 12. Below the lamps is arranged the plane reflector 13. About the source of light and above the lamps is arranged the reflector 14.

The reflectors and the lamps are arranged in such a manner as to illuminate the side walls of the room to a convenient height above the floor (to the point *a*) by direct rays from the lamps. The floor of the room and the part of the side walls below the point *a* will be illuminated only by diffused light from the reflectors.

The source of light 10 is composed of a lamp holder 16, sockets for the lamps, electric lamps 17 and means for securing the lamp holder to the ceiling, composed of a cross strip 32 secured to the ceiling by a screw 41, threaded rods 33 moveably attached to the cross strip, nuts 38, 39 for clamping the perforated part 34 of the lamp holder to the threaded rods 33. The sockets 18 are secured in openings in the lamp holder by screws 19. The lamps 17 may be provided with an upper reflecting surface 20.

The upper reflector 14 has a central open-

ing and is composed of a translucent or opaque plate 30 preferably of translucent leather or painted metal supported by outer metal rings 25, 26 and inner metal rings 28, 29. The ring 29 is attached to the ring 27, which is provided with strips 36 suspended by the nuts 40 on the threaded rods 33. The lower reflector 13 is composed of a translucent and light diffusing plate 24 preferably 10 of translucent leather supported by metal rings 21, 22. The upper ring 22 is attached to a metal ring 23, from which the reflector 13 is suspended by means of detachable metal hooks 31 resting on the ring 29. The reflectors and rings may be of circular, square, 15 oval or other shape. The relative heights of the lamps and the reflectors are varied by varying the heights of the nuts 38, 39, 40, and effects that the point *a*. may be positioned 20 at desired heights in rooms of different size and shape.

Refracting pendants may be arranged between the reflectors and suspended from the higher of them. These pendants 35 serve 25 for shielding the direct light from part of the side walls and may be arranged non visible for the eye.

The upper reflector may consist of a group 30 of more reflectors i. e., as shown in Fig. 2, where the group consists of the two reflectors 15, 44. Thus the general feature of my lighting apparatus has an upper group of reflectors, which group consists of one or more reflectors. Of all the reflectors always 35 a higher placed reflector is larger than a lower placed reflector.

The visible part of the reflectors may be painted with decorative figures, whereby the lighting apparatus acts as a ceiling piece 40 both at daylight and when the lamps are lighted.

The lighting apparatus is described and 45 preferably adapted for being secured to the ceiling of a room but may also be secured to the side wall of a room.

Having thus fully described my invention, what I claim as new, and desire to secure by Letters Patent of the United States is:

1. The combination with a source of light, 50 of a lower substantially plane reflector and an upper plane reflector group, the lower reflector being translucent and light diffusing and arranged below the light source, and in the way of at least the vertical and near- 55 vertical direct rays from the light source, higher placed reflector being larger than lower placed reflector.

2. The combination with a source of light, 60 of a lower substantially plane reflector and an upper plane reflector group, the source of light being composed of a lamp holder and lamps, the lower reflector being translucent and arranged below the lamps, higher placed reflector being larger than lower placed reflector, all reflectors being light diffusing. 65

3. The combination with a source of light, of an upper and a lower substantially plane reflector, the source of light being composed of a lamp holder and lamps, the lower reflector being translucent and light diffusing and 70 arranged below the lamps, the upper reflector being larger than the lower reflector and light diffusing.

4. The combination with a source of light, of an upper and a lower substantially plane reflector, the source of light being composed of a lamp holder and lamps, the lower reflector being translucent and light diffusing and arranged below the lamps, the upper reflector being larger than the lower reflector and 75 arranged above the lamps.

5. The combination with a source of light, of an upper and a lower substantially plane reflector, the source of light being composed of a lamp holder and lamps, the lower reflector being translucent and light diffusing and arranged below the lamps, the upper reflector being larger than the lower reflector and having a substantially central opening for 80 the source of light, the opening being smaller than the lower reflector.

6. The combination with a source of light, of an upper and a lower substantially plane reflector, the source of light being composed of a lamp holder and lamps, the lower reflector being translucent and light diffusing and arranged below the lamps, the upper reflector being light diffusing and larger than the lower reflector and arranged above the lamps and having a substantially central opening 95 for the source of light, the opening being smaller than the lower reflector, the two reflectors being adjustably attached to the source of light.

7. The combination with a source of light, 100 of an upper and a lower substantially plane reflector, the source of light being arranged between the reflectors and composed of a lamp holder and lamps, the lamps being electrical incandescent lamps, sockets for the 105 lamps being secured in apertures in the lamp holder, and means for securing the lamp holder to the ceiling being adjustably attached to the lamp holder.

8. The combination with a source of light, 110 of an upper and a lower substantially plane reflector, the source of light being composed of electric lamps, a hollow lamp holder, sockets for the lamps, secured to the lamp 115 holder, and means for securing the lamp holder to the ceiling, means for adjustably supporting the reflectors, the lower reflector being translucent and light diffusing and arranged below the lamps, the upper reflector being light diffusing and larger than the lower reflector, being arranged above the lamps, and having a substantially central 120 opening for the source of light smaller than the lower reflector, refractive pendants being secured to the upper reflector.

9. The combination with a source of light, of an upper and a lower substantially plane reflector, the source of light being composed of electric lamps, a hollow lamp holder, sockets for the lamps and means for securing the lamp holder to the ceiling, the lower reflector being arranged below the source of light, the upper reflector being larger than the lower reflector, being arranged above the lamps and having a substantially central opening for the source of light, the opening being smaller than the lower reflector, both the reflectors being substantially circular and parallel and composed of translucent and light diffusing leather attached to metal rings, the metal rings of the upper reflector being adjustably connected to the means for securing the lamp holder to the ceiling, the metal rings of the lower reflector being detachably connected to the metal rings of the upper reflector by metal hooks.

In testimony whereof I affix my signature.
ERNST EMANUEL HOLMQVIST.
